UNITED STATES PATENT OFFICE.

BAXTER M. ASLAKSON, OF SALEM, OHIO.

ENGINE-GOVERNOR.

1,007,661.

Specification of Letters Patent.

Patented Nov. 7, 1911.

Application filed January 14, 1908. Serial No. 410,728.

To all whom it may concern:

Be it known that I, BAXTER M. ASLAKSON, a citizen of the United States, and resident of Salem, in the county of Columbiana and State of Ohio, have invented certain new and useful Improvements in Engine-Governors, of which the following is a specification.

My invention relates to governors for engines and the object of the same is to provide a governor of simple and durable construction in which the fly-weights will move in alinement with each other and exert their force against a single spring. Further features of novelty are clearly disclosed in the subsequent detailed description.

In the accompanying drawings,—Figure 1, is a cross sectional view through the body of the governor casing, disclosing an end view of the fly-weights and supporting levers therefor. This view further illustrates the pedestal which supports the rotating parts and through which power is transmitted to drive the governor. Fig. 2, is a side view of the fly-weights mounted on their supporting levers within the governor casing, and a side view of the pedestal. Fig. 3, is a plan view of the fly-weights and levers within the governor casing, the latter being shown in section. Fig. 4, is a perspective view of the casing base and the supporting levers with the fly-weights removed from the latter.

A, indicates a pedestal in the center of which is a shaft B vertically supported and carrying on its upper end the base C, of the casing, the upper part or body C' of which forms a cover for the fly-weights and levers which are mounted on the base C.

Cast integral with the base C, are eight vertical brackets C², C², etc., spaced an equal distance on each side of a line drawn across the base C at its center, and disposed four on each side of said line respectively. In the upper end portion of each of said brackets is a hole which receives one end of a bolt D, extending across to the opposite bracket. Pivoted on the bolts are four U-shaped bracket-levers E, containing holes leading through their cylindrical base portions, through which the bolts D pass to support said levers in operating position.

The two end bracket levers E are each provided with a longitudinally extending lever E' cast integral therewith and having a boss E², located in nearly vertical aline-

ment with a boss F of the vertical links F', which connect the ends of the levers E' and the sleeve G. Locked in each boss E² is a pin H, which is held in the boss by a set screw I, serving to connect the lever E' to the link F'.

Two fly-weights J, each of which are rectangular in cross section, are held in pivotal relation to the bracket-levers E by cross pins N, N, etc., and are free to swing apart from each other when subjected to centrifugal force, but are limited in the distance they can so move, by a pair of longitudinally extending rods K, provided with enlarged ends forming shoulders adapted to abut against two bosses P, P, cast on the weights, supporting strips L which hold said rods in position being bolted to the fly-weights by bolts M, M, etc. The fly-weights each contain a cylindrical bore extending longitudinally therethrough in which a spiral spring O is located. A plate Q closes one end of said bore and is connected to one of the fly-weights by bolts Q'. A threaded bolt Q² passes through the plate Q, with the bolt-head resting against the outside face of said plate and the thread of the bolt fitting into a nut held by one end of the spring, so that by turning the bolt Q², the tension of said spring may be changed. The bolt Q² is held in its adjusted position by a set screw S bearing within a hole in the plate Q, drilled at a right angle to the axis of the bolt Q².

The opposite end of the spring O is formed in a loop which extends into an opening formed in a plate R, which is a duplicate of the plate Q and is held to the fly-weight in the manner before described, and one end of the set screw S' in the plate R, projects through said loop, indicated at T, to hold same to said plate, as will be readily understood.

The sleeve G contains an annular groove in which is fitted a ring indicated by V (shown in dotted lines) and adapted to remain stationary while the sleeve revolves, and fastened to this ring on opposite sides thereof is a bifurcated lever V, hinged at one end to an integral arm of the pedestal at W, and pivotally connected at its opposite end to a rod X, which carries at its lower end a piston somewhat less in diameter than the cylindrical bore in a chamber Y, the latter being pivoted to the pedestal at Y'. The chamber Y is filled with liquid which is operated on by the piston to prevent undue shock in the governor.

by reason of sudden fluctuations of load on the engine.

Z indicates the gear wheel secured on the governor shaft B, and in mesh with a similar wheel connected to a driven shaft of the engine and by means of which the governor is rotated.

- In operation, the engine drives the governor in the manner intimated, rotating the vertical shaft B, yoke G and casing base C, which supports the fly-weights J, and said fly-weights, being disposed on opposite sides of the center of the plate C, are separated by centrifugal force to a predetermined degree according to the speed of the governor, against the resistance of the spring O, the tension of which may be set to allow a certain relative movement of the fly-weights at a given speed of rotation of the plate C.
- The outward movements of the fly-weights are transmitted to the bracket levers E and E' which are swung on their pivots D, causing their levers E' to raise the links F and yoke G, and consequently, upwardly swinging the lever V and thereby turning the shaft W' to which lever V is connected, a certain distance to control the valve or valves of the engine which are connected to said shaft W', as will be easily understood.
- The casing presented by the base C, and body C', may be made to be fairly air tight, the openings through which the links F' pass being a close sliding fit, and the depressed character of said base adapting it to be filled with oil or grease to keep the parts thoroughly lubricated. The parallel position of the supporting bracket-levers causes the fly-weights to remain in relative alinement at all times and the position of the weights in the drawings is the position they would occupy when the governor is being rotated at the normal speed thereof and at the normal speed of the engine. The side rods K limit the distance the fly-weights can separate from each other, and in making very light governors for some purposes it is obvious that the two inner supporting brackets E could be dispensed with by allowing the side links K to act to hold the bores of the fly-weights in alinement and fitting them to the sides of the fly-weights so as to secure a smooth sliding action between the parts, but in this case I should prefer to hinge the supporting brackets nearer the middle of the fly-weights.

The device is strong, simple and compact, is not easily deranged, and most of the parts are of duplicate construction which admits of low cost of construction and repairs.

Having thus described my invention, what I claim as new and desire to secure by Letters Patent, is—

1. A governor comprising a base plate having a practically closed bottom and having a plurality of brackets extending up-

ward therefrom and carrying a plurality of bracket-levers, fly-weights connected to and directly supported by said levers and containing alined bores, a spring within said bores and secured at its ends by parts at the outer portions of the weights, the parts at one end of the spring including means for adjusting the spring tension, a cover to inclose said parts, and means through which said governor may be rotated.

2. A governor comprising a base plate having a practically closed bottom and carrying a plurality of bracket-levers extending upwardly therefrom, two of which are located at each side of each of the fly-weights, fly-weights connected to and directly supported by said levers and containing alined bores extending therethrough, a spring within said bores and secured at one end to the outer portion of one of the weights, and having a nut at the other end, a bolt supported in bearing relation to the outer end of the other weight and engaging said nut, a cover inclosing said parts, and fitted to said base plate, and means through which said governor may be rotated.

3. A governor comprising a base plate having a practically closed bottom and carrying a plurality of bracket-levers extending upwardly therefrom, two of which are located at each side of each of the fly-weights, fly-weights connected to and directly supported by said levers and containing alined bores extending therethrough, a spring within said bores and provided with a loop at one end and a nut at the other, plates bolted to the outer ends of the weights, bolts bearing in said plates and engaging the spring loop and nut respectively, a cover fitting said base plate and inclosing said parts, and means through which said governor may be rotated.

4. A governor comprising a base carrying a plurality of bracket-levers extending upwardly therefrom, two of which are located at each side of each of the fly-weights, fly-weights connected to and directly supported by said levers and having external stops, rods connected to said weights but permitting the relative movement thereof, said rods having end enlargements adapted to contact with said stops, a spring connecting said weights, and means through which said governor may be rotated.

5. A governor comprising a base plate having a practically closed bottom and a plurality of brackets extending upward therefrom and carrying a plurality of levers, two of which are located at each side of the fly-weights, fly-weights connected to and supported by said levers and containing alined bores, a spring within said bores and secured at its ends to said weights, means for adjusting the tension of said spring, means through which said governor may be rotated.

rotated, and means for inclosing the working parts.

6. A governor comprising a base plate having a practically closed bottom and a plurality of brackets extending upward therefrom and carrying a plurality of levers, fly-weights connected to and directly supported by said levers and containing alined bores, a spring within said bores and secured at its ends to said weights, a cover having a depending wall the lower edge of which is fitted to said base plate and incloses the fly-weights, and means through which said governor may be rotated.

15 7. A governor comprising a base plate having a practically closed bottom and carrying a plurality of bracket-levers which extend upward therefrom, fly weights directly connected to and supported by said levers and containing alined bores extending therethrough, a cap at the outer end of each of said bores, a spring which directly connects said caps together, means for adjusting the tension of said spring, and a 25 cover having depending sides the lower edge of which rests on said base plate and incloses said fly-weights.

8. A governor comprising a base plate having a practically closed bottom and having a plurality of brackets extending upward therefrom, a plurality of bracket-levers connected thereto, fly weights directly connected to and supported by said levers and containing alined bores extending there- 35 through, a cap at the outer end of each of said fly weights, a spring within said bores and directly connecting said caps, means for adjusting the tension of said spring, an inclosing cover for said parts, and means 40 through which said governor may be rotated.

9. A governor comprising a base plate having a practically closed bottom and having a plurality of brackets extending upward therefrom, a plurality of bracket-levers connected thereto, fly weights directly connected to and supported by said levers and containing alined bores extending therethrough, a cap at the outer end of each 45 of said weights, a spring within said bores and secured to and directly connecting said caps, a cover inclosing said fly weights and connected to said base plate, and means through which said governor may be rotated.

55 10. A governor comprising a base plate having openings formed in the bottom thereof on its median line, and having a plurality of brackets extending upward therefrom, a plurality of upwardly extending links connected to said brackets, fly-weights directly connected to and supported by said links and containing alined bores extending therethrough, a cap at the outer end of each 60 of said weights, a spring within said bores

and secured to said caps, a bell-crank lever for each of said fly-weights, the upper end of which is connected directly thereto and the lower end of which extends longitudinally of the base plate to the median line 70 thereof, links connecting the ends of said bell-crank lever and extending through said openings in the base, a sleeve connected to the lower ends of said last named links, a lever actuated by said sleeve, and means extending through said sleeve for rotating said base plate.

11. A governor comprising a base plate having openings formed in the bottom thereof on its median line, and having a plurality of brackets extending upward therefrom, a plurality of upwardly extending links connected to said brackets, fly-weights directly connected to and supported by said links and containing alined bores extending 85 therethrough, a cap at the outer end of each of said weights, a spring within said bores and secured to said caps, side links connecting said fly-weights to limit their outward movement, a bell-crank lever for each 90 of said fly-weights, the upper end of which is connected directly thereto and the lower end of which extends longitudinally of the base plate to the median line thereof, links connecting the ends of said bell-crank lever 95 and extending through said openings in the base, a sleeve connected to the lower ends of said last named links, a lever actuated by said sleeve, and means extending through said sleeve for rotating said base plate.

100 12. A governor comprising a base plate having openings formed in the bottom thereof on its median line, and having a plurality of brackets extending upward therefrom, a plurality of upwardly extending links connected to said brackets, fly-weights directly connected to and supported by said links and containing alined bores extending therethrough, a cap at the outer end of each 105 of said weights, a spring within said bores and secured to said caps, side links connecting said fly-weights to limit their outward movement, a bell-crank lever for each of said fly-weights, the upper end of which is connected directly thereto and the lower end 110 of which extends longitudinally of the base plate to the median line thereof, links connecting the ends of said bell-crank lever and extending through said openings in the base, a sleeve connected to the lower ends 115 of said last named links, a lever actuated by said sleeve, means extending through said sleeve for rotating said base plate, and a cover for said base plate, the depending sides of which assist in inclosing said fly- 120 weights and levers.

13. A governor comprising a base plate having openings formed in the bottom thereof on its median line, and having a plurality of brackets extending upward 125

therefrom, a plurality of upwardly extending links connected to said brackets, fly-weights directly connected to and supported by said links and containing alined bores extending therethrough, a cap at the outer end of each of said weights, a spring within said bores and secured to said caps, a bell-crank lever for each of said fly-weights, one of which is located at one side of one of the 10 said weights and the other of which is located at the opposite side of the other of said weights, the upper ends of each of which are connected respectively to one of said fly-weights and the lower ends of each 15 of which extend longitudinally of the base

plate to the median line thereof, links connecting the ends of said bell-crank lever and extending through said openings in the base, a sleeve connected to the lower ends of said last named links, a lever actuated 20 by said sleeve, and means extending through said sleeve for rotating said base plate.

Signed at New York in the county of New York and State of New York this tenth day of January A. D. 1908.

BAXTER M. ASLAKSON.
